UNITED STATES PATENT OFFICE.

JOHN N. MOORE, OF GREAT FALLS, MONTANA.

STAPLE.

1,072,974.

Specification of Letters Patent.

Patented Sept. 9, 1913.

Application filed April 3, 1913. Serial No. 758,727.

To all whom it may concern:

Be it known that I, JOHN N. MOORE, a citizen of the United States, residing at Great Falls, in the county of Cascade and State of Montana, have invented certain new and useful Improvements in Staples, of which the following is a specification.

The primary object in view in devising the staple of this invention has been to provide a fastener of the type mentioned, particularly adapted for securing fence wire to fence posts, a staple which is formed in such a manner as to grip a wire peculiarly, independently of the impingement of the staple incidental to driving the same into the post.

More specifically speaking, the staple of my invention is of the two-legged type, and is preferably made by bending flat metal into a special shape to afford a peculiar longitudinal rigidity, facilitating the driving home of the staple in a post or other object, this formation at the same time necessitating the kinking of a wire engaged by the staple in such a way as to eliminate liability of slipping of the wire when once impinged by the fastener.

For a full understanding of the present invention, reference is to be had to the following description and to the accompanying drawings, in which—

Figure 1 is a perspective view showing the fastener or staple driven in a wooden fence post and properly engaged with a fence wire. Fig. 2 is a sectional view of the same. Figs. 3 and 4 are sectional views of modified forms of the staple as used in connection with a plastic post. Fig. 5 is a fragmentary elevation of the post shown in Fig. 4 and illustrating the location of the openings which receive the legs of the staple. Figs. 6 and 7 are edge views, respectively, of the plastic post and wooden post staples. Fig. 8 is a similar view of a modification. Fig. 9 is an end view of the staple as when driven into a post and showing clearly its manner of impingement with a wire as well as the peculiar deflection or kinking of the latter. Fig. 10 is a side elevation of the staple alone.

Throughout the following detail description and on the several figures of the drawings, similar parts are referred to by like reference characters.

A in the drawings denote a wooden fence post and B and C are plastic fence posts.

D indicates a fence or other wire, it being understood, of course, that these parts are shown and thus designated merely to illustrate the practical application of the invention which may be used in many other ways.

Describing specifically the staple, it may be noted that the latter is of integral construction and comprises essentially a head portion consisting of a central web 1 and off-standing sides 2 extending substantially at a right angle to said web and consisting of extensions from the opposite edges of the latter. The legs 3 of the staple are longitudinal extensions or projections of the sides 2 and these legs are arranged in parallel planes spaced from one another owing to the relation of the sides 2 and the web 1. The adjacent edges of the legs 3 are preferably curved outwardly, or away from each other toward the free terminals of the same so that each leg is practically a penetrating point and, so considered, may be said to have a divergent relation, as shown clearly in Fig. 10.

It will be apparent that the head portion of the staple is longitudinally reinforced by reason of the angular arrangement of the sides 2 in respect to the web 1 and this reinforcement is not only advantageous to render the head rigid for resisting the blows of a driving implement but, as obvious from the drawings, the depression of the sides affords a corresponding arrangement of the legs 3 of the staple, forming spaced bearing points 3' at which the inner edges of the legs 3 may be impinged with the wire D, whether the staple is driven into a wooden post A or applied to a plastic post, such as B or C, in Figs. 3 and 4, respectively. When employed for plastic posts, the staple will be of a greater length preferably than when used for wooden posts so that the legs of the fastener may be passed entirely through openings in the post, as shown in Fig. 3 and 100 then bent apart to form holding stops 3a. However, the legs of the staple, as illustrated in Fig. 4, may be entered in diverging sockets C' of the post, these sockets being molded in the post as would also be the 105 openings formed in the post B. When applied to the post D, the driving of the staple in place causes divergence of its legs that operate in the sockets C', thereby insuring retention of the device from displacement. 110 Spaced bearing points 3' of the legs 3 which will cause the peculiar kinking or deflection

of a wire engaged under tension by the staple, are quite clearly shown in Fig. 9. In Fig. 8, the legs of the staple are peculiarly curved at points intermediate their ends, as shown at 3^b, this being advantageous when it is driven into the sockets or openings of a plastic post.

A staple made in accordance with the invention will preferably be cut from a blank 10 of sheet metal, and bent into proper shape by the application of suitable dies. The staple therefore affords a very advantageous article of manufacture, owing to its very cheap but efficient structure.

15 Having thus described the invention, what is claimed as new is:

1. A staple comprising a head consisting of a central web having at its longitudinal edges off-standing sides projecting in opposite directions from the web, the said sides being formed with longitudinal extensions forming legs for the staple arranged in parallel spaced planes.

2. A staple comprising a head consisting of a central web having at its longitudinal edges off-standing sides projecting in opposite directions from the web, the said sides being formed with longitudinal extensions forming legs for the staple arranged in parallel spaced planes, the adjacent edges of the legs curving outwardly to their free terminal points.

3. As a new article of manufacture, a fence wire staple consisting of a piece of

sheet metal bent at an intermediate portion 35 to form a central web, and off-standing sides projecting in opposite directions from said web, each side having an extension projecting some distance from the web and forming a leg.

4. As a new article of manufacture, a fence wire staple of integral structure consisting of a plate bent at an intermediate portion to provide a head composed of a central web, and side portions extending 45 practically at a right angle from the opposite edges of said web and in opposite directions, said sides being formed with integral extensions constituting legs for the staple.

5. As a new article of manufacture, a fence wire staple of integral structure consisting of a plate bent at an intermediate portion to provide a head composed of a central web, and side portions extending practically at a right angle from the opposite edges of said web and in opposite directions, the said sides being formed with longitudinal extensions terminating some distance from the web and forming legs, the outermost edges of said legs being parallel, 60 while their inner edges diverge toward the free terminals of the legs.

In testimony whereof I affix my signature in presence of two witnesses.

JOHN N. MOORE.
